(74) *Attorney, Agent, or Firm* — Bachman & LaPointe, P.C.

(57) **CLAIM**

The ornamental design for a bottle, as shown and described.

DESCRIPTION

FIG. 1 is a top perspective view of a first embodiment of my new design for a bottle;

FIG. 2 is a bottom perspective view thereof;

FIG. 3 is a side view thereof;

FIG. 4 is another side view thereof, opposite to FIG. 3;

FIG. 5 is a top view thereof;

FIG. 6 is a bottom view thereof;

FIG. 7 is a top perspective view of a second embodiment of my new design for a bottle;

FIG. 8 is a bottom perspective view thereof;

FIG. 9 is a side view thereof;

FIG. 10 is a side view thereof, opposite to FIG. 9;

FIG. 11 is a top view thereof; and,

FIG. 12 is a bottom view thereof.

The portions of the bottle shown in broken line form no part of the claimed design.

1 Claim, 10 Drawing Sheets
